UNITED STATES PATENT OFFICE.

WILLARD FAGAN, OF LEWIS TOWNSHIP, CLAY COUNTY, INDIANA.

CARPET-STRETCHER.

No. 909,072.

Specification of Letters Patent.

Patented Jan. 5, 1909.

Application filed July 24, 1908. Serial No. 445,262.

To all whom it may concern:

Be it known that I, WILLARD FAGAN, a citizen of the United States of America, residing at Lewis township, in the county of 5 Clay and State of Indiana, have invented new and useful Improvements in Carpet-Stretchers, of which the following is a specification.

This invention relates to carpet stretchers, 10 and one of the principal objects of the same is to provide a convenient, adjustable and efficient device for stretching carpets at various angles.

Another object of the invention is to provide a device composed of detachable sections for stretching carpets in large or small rooms at various angles lengthwise, crosswise and diagonally across the room.

These and other objects may be attained 20 by means of the construction illustrated in the accompanying drawing, in which,—

Figure 1 is a side elevation of a carpet stretcher embodying my invention. Fig. 2 is a plan view of the same. Fig. 3 is a vertical sectional view taken on the line 3—3 of Fig. 1, looking in the direction indicated by the arrows. Fig. 4 is a detail perspective view of the stretcher plate. Fig. 5 is a detail perspective view of the bifurcated lever for 30 operating the stretcher member.

Referring to the drawing, the numeral 1 designates the extension bar. At the outer end of this bar 1 is a buffer 2 of leather, rubber or other suitable material and designed 35 for the purpose of bearing against the baseboard of a room and to prevent marring the same. The stretcher bar 3 is mounted to slide on the extension bar 1, said bar 3 having secured at its outer end a metal stirrup 4 40 which encircles the bar 1, said stirrup being secured to the stretcher bar 3 by means of a suitable rivet 5. A similar stirrup 6 is connected to the end of the extension bar 1 by means of a suitable rivet or fastener 7, said 45 stirrup 6 being adapted to slide upon the stretcher bar 3. The stirrups 4 and 6 have a slight pivotal action on the fasteners 5 and 7, and hence when extended will bind upon the bars 1 and 3 and hold said bars in ad- 50 justed position.

The stretcher member 8 consists of a bar having secured to its inner end a metal stirrup 9. A similar stirrup 10 is secured to the outer end of the bar 3, and thus the stretcher 55 member 8 is designed to slide upon the bar 3. Connected to the outer end of the member 8

is a stretcher plate 11, said plate having a series of points or prongs 12 projecting downward therefrom, said prongs or points being arranged in rows in staggered relation, as 60 shown in Fig. 4. The stretcher plate is provided with a lug 13 having a hole 14 therein. Extending through the hole 14 is a screw 15 provided with a winged nut 16 for clamping said plate to the stretcher member 8. 65

Secured in a suitable bracket 17 connected to the bar 3 is a rack bar 18 having a series of notches and teeth formed therein. A lever 19 having a handle 20 and bifurcated members 21 is provided with a ratchet plate 22 designed to engage the notches in the rack bar 18. The members 21 have downwardly extending lugs 23 designed to engage studs 24, one projecting from each side of the stretcher member 8. 75

The operation of my invention may be briefly described as follows: If the room is of sufficient area to permit the use of the extension bar 1, the buffer 2 is placed against the baseboard, and the stretcher 80 member 8 is pushed inward to the position shown in Fig. 1. The stretcher plate 11 may be turned at the required angle relatively to the member 8 and the winged nut 16 tightened to hold said plate in position. 85 The handle 20 of the lever is then thrown to the left in Fig. 1 to extend the stretcher member 8, after which the carpet is tacked in place. It will be understood that the extension bar 1 may be removed when the 90 stretcher is to be used in small rooms.

My invention is of simple construction, is strong, durable and efficient in use, can be manufactured at low cost and will operate on all kinds of carpets. 95

I claim:

A carpet stretcher comprising extensible members, a stretcher member mounted on one of said members, a stretcher plate adjustably connected to the stretcher member, a rack bar on one of said extensible members, and a bifurcated lever having downturned lugs to engage studs on the stretcher member, said lever having a ratchet plate to engage the teeth of said rack bar. 100 105

In testimony whereof I affix my signature in presence of two witnesses.

WILLARD FAGAN.
